UNITED STATES PATENT OFFICE.

FREDERIC B. BALDWIN, OF NEW YORK, N. Y.

ACETYLENE-GAS LAMP.

1,115,157.

Specification of Letters Patent. Patented Oct. 27, 1914.

Application filed March 30, 1916. Serial No. 555,862.

To all whom it may concern:

Be it known that I, FREDERIC B. BALDWIN, a citizen of the United States, residing at New York, borough of Richmond, and State of New York, have invented certain new and useful Improvements in Acetylene-Gas Lamps, of which the following is a full, clear, and exact description.

This invention relates to certain improvements in acetylene gas lamps, and more particularly to that type of such lamps which comprise in the same structure a gas generator and a burner.

The object of the invention is to produce a lamp of the character referred to in which simple and efficient means, which may be cheaply constructed and readily operated, are provided for the purpose of controlling the flow of water from the water chamber to the carbid reservoir.

With this and other objects not specifically referred to in view, the invention consists in certain constructions and in certain parts, improvements and combinations as will be hereinafter fully described and then specifically pointed out.

The accompanying drawing shows a vertical section through a miner's lamp embodying my improvement.

As generally constructed, my lamp is constructed in two main parts, the upper chamber A, being the water reservoir, and the lower, separable chamber B, the carbid container.

K is the gas-burner, suitably connected by a tube with the upper part of the carbid chamber, and L is a reflector.

The lamp is designed to be provided with a handle or means for attachment to the miner's cap. The water container may be provided with an inlet N.

O is a tube leading from the water container to the carbid chamber.

P is a threaded opening in the cover of the water chamber, and M is a screw-threaded plug fitting in said opening and mounted upon, or integral with, a short tube F that extends to or nearly to the bottom of the water chamber. Upon the lower end of F is mounted a valve H, which is preferably composed of a metal disk and a rubber gasket. By turning the plug M the valve H may be opened sufficiently to allow the water to drip into the carbid chamber, or

seated so as to close the upper opening of 65 the water tube O.

The plug M is perforated, so that the raking wire D may be extended through it and the tubes F and C into the carbid chamber. One of the objects of this wire is to afford 60 means to break away any slaked carbid that may accumulate about the mouth of the tube C during the operation of the lamp, and thus avoid clogging of the orifice. At the lower end of the wire D may be attached a 65 plug J, tapering if desired toward its lower end, as shown.

In operation of the lamp, the water dripping in small quantities through the tube O follows the wire D and drops from its end 70 upon the carbid. By increasing the surface of the extremity of wire D, as by the plug J, the danger of throttling the action of the water by clogging the end of the wire is much diminished, and the flow of the water 75 all over the plug J increases the even distribution of water to the carbid, as well as decreasing the danger of clogging. Occasional stirring, by the wire D, is all that is required.

I believe that the operation and advantages of my invention will be fully understood by those familiar with this class of apparatus from a reading of the foregoing description.

What I claim as my invention is:

1. In an acetylene gas lamp, the combination with a carbid chamber, of a superposed water chamber, a water tube leading from the water chamber into the carbid chamber, an elastic plug for controlling the flow of water through the tube, a raking wire extending freely through the plug and through the tube, and means independent of the raking wire for positively controlling the position of the plug from the outside of the lamp, said wire having a plug on its lower end exposed to the carbid and increasing the even distribution of the water to the carbid.

2. In an acetylene gas lamp, the combination with a carbid chamber, of a superposed water chamber, a water tube leading from the water chamber to the carbid chamber, a tube in the water chamber accessible from the outside of the lamp, a threaded connection between the tube and the top of the lamp, an elastic plug carried by the tube and serving to control the flow of water

through the water tube, and a raking wire extending through both tubes, said wire having a plug on its lower end exposed to the carbid and increasing the even distribution of the water to the carbid.

3. In an acetylene lamp, the combination with a carbid chamber, of a superimposed water chamber, a water tube leading from the water chamber into the lower portion of the carbid chamber so as to be exposed to the slaked carbid therein, a movable wire extending through said water chamber and said water tube, and provided with a plug on its lower end within the carbid chamber, diminishing the danger of throttling the action of the water, and increasing the even distribution of water to the carbid.

4. In an acetylene lamp, the combination with a carbid chamber, of a superimposed

water chamber, a water tube leading from the water chamber into the lower portion of the carbid chamber so as to be exposed to the slaked carbid therein, a movable wire extending through said water chamber and said water tube, and provided with an enlargement on its lower end within the carbid chamber, said enlargement diminishing the danger of throttling the action of the water, and increasing the even distribution of water to the carbid.

In testimony whereof I affix my signature in the presence of two subscribing witnesses.

FREDERIC E. BALDWIN.
